UNITED STATES PATENT OFFICE

CHARLES O. REEPS, OF CHICAGO, ILLINOIS, ASSIGNOR, BY MESNE ASSIGNMENTS, TO NATIONAL LAUNDRY MACHINERY COMPANY, INC., OF WILMINGTON, DELAWARE, A CORPORATION OF DELAWARE

IRONING MACHINE

Application filed February 21, 1928. Serial No. 255,946.

My present invention relates in general to a method of and an apparatus for ironing, and more particularly to an improved ironing machine of the same general character as that disclosed in my co-pending patent application, Serial No. 212,651, filed August 13th, 1927.

In the conventional ironing machine the article to be ironed is placed on the stationary buck, and the pressing head is thereafter moved downwardly into cooperation with the stationary buck to apply pressure and heat to the article thereon, whereby the same is ironed. I have found that this method of ironing is not as satisfactory as desired for the reason that the article is not sufficiently stretched on the buck to eliminate wrinkles and other irregularities therefrom. This means that the articles being ironed are irregularly pressed and as a result do not come out of the machine in as good a condition as is desired.

I propose to remedy this difficulty by providing a stationary buck having a convex pressing surface adapted to cooperate with a concave ironing surface in the movable pressing head. Moreover, I purposely make the curvature of the ironing head slightly greater than the curvature of the convex ironing surface on the stationary buck so that when the ironing head is moved into cooperation with the buck it will serve to contemporaneously stretch and iron the article on the buck.

Then, too, it has been my observation that articles of clothing and the like which are ironed while in a moist or damp condition do not leave the conventional ironing machine after being ironed in a completely dry condition, thus necessitating a subsequent drying operation which is usually accomplished by hanging the ironed article any place where it will be cooled and dried by the natural circulation of air.

It is the aim of my invention to provide an ironing machine which not only irons articles placed therein but also completely dries the articles during the ironing operation and while they are on the stationary buck.

I also find from experience that in the conventional ironing machine due to the

moist condition of the article being ironed the moisture is all forced to the lower side of the article when the heated pressing head is applied thereto, which results in only the top side of the article being finished, or in other words the side subjected to the heated ironing surface.

This type of ironing work might be satisfactory in the case of rough dry work, such as sheets and the like, but it surely is not fully satisfactory in the case of other types of articles, of a finer nature, such for example as handkerchiefs, scarfs, etc.

I propose to provide an ironing machine adapted to iron and finish articles placed therein on both sides, thus completely eliminating the above mentioned undesirable feature.

An object of my invention is to provide an improved ironing machine of simple and inexpensive construction and adapted to turn out a much better grade of ironed work than the conventional type of machine.

Another object of my invention resides in the provision of an ironing machine wherein the ironing is effected by the circulation of heated air through the ironing buck and head of the machine.

Still another object of this invention has to do with the provision of an ironing machine adapted to iron and finish articles on both sides.

A further object is the provision of an ironing machine having cooperable convex and concave ironing members, the curvature and ironing surface of one of the ironing members being slightly less than that of the other ironing member, whereby the article to be ironed, placed therebetween, is completely stretched during the ironing operation, thus eliminating wrinkles and any other irregularities in the article ironed, and thereby causing the machine to turn out a high grade of ironed work.

A still further object of the invention is to provide an ironing machine including relatively movable cooperable ironing members, one of which is adapted to have heated air forced therethrough and through the article being ironed, and the other of which has suc-

tion means connected to it for withdrawing the heated air from the article ironed so as to facilitate cooling and drying of the article.

In accordance with the general features of the present invention, I provide an ironing machine including a stationary ironing buck cooperable with a movable ironing head, and means, such as a blower, for forcing heated air into and through the head and for applying suction to the buck for withdrawing the dissipated heated air so as to cool and dry the article being ironed.

Another feature of the invention resides in the provision of an ironing machine including cooperable ironing members, one of which having a convex ironing surface and the other of which having a concave ironing surface adapted for cooperation with the convex surface whereby the article being ironed therebetween is substantially stretched to remove wrinkles from the same, one of said surfaces being defined by a sheet of wire mesh adapted to enhance the finish applied to the article.

Another feature is the provision of filter means in the ironing head for removing foreign matter from the air being circulated prior to coming into contact with the article being ironed.

Other objects and advantages of my invention will more fully appear from the following detailed description taken in connection with the accompanying drawings, which illustrate a single embodiment thereof and in which:

Figure 1 is an end elevation of my novel ironing machine;

Figure 2 is a front view of this ironing machine illustrating the connections between it and the motor for operating the same as well as the connections between it and a blower for heating and drying the article being ironed;

Figure 3 is a plan view of the ironing machine;

Figure 4 is an enlarged fragmentary sectional view taken on substantially the line IV-IV of Figure 3, looking in the direction indicated by the arrows;

Figure 5 is an enlarged fragmentary sectional view taken on substantially the line V-V of Figure 3 looking upwardly, and

Figure 6 is a sectional view taken on substantially the line VI-VI of Figure 5 looking downwardly.

In the drawings:

Like reference characters designate similar parts throughout the several views.

It is thought that my novel method of ironing will be apparent from a description of the apparatus for producing the same.

The reference character 10 designates generally a support for the ironing machine including standards 11 and a top 12. Secured to the top 12 is a stationary ironing buck designated generally by the reference

character 13 cooperable with a movable ironing head 14 which is carried by spaced arms 15 secured to the standards 11 of the support 10.

The stationary ironing buck 13 includes a longitudinal hollow casting 17 in which is a heating chamber 18. The upper part of this buck is provided with a convex top 20. That is to say, I provide the stationary buck with an ironing surface which is of a predetermined curvature and is formed transversely convex. This convex top 20 is provided with a plurality of openings or perforations 21 and is covered by the usual ironing cloth 22. The bottom of the casting 17 rests upon and is secured to a tubular pedestal 23 which is in turn fastened to the top 12 of the support 10. Extending through the bore 24 of the pedestal 23 is a relatively large air pipe 25 which has its upper end threaded into the bottom of the casting 17 and disposed in communication with chamber 18 in the stationary buck 13.

As shown in Figure 2, this pipe 25 extends downwardly through a suitable opening in the top 12 of the support 10 and between the standards 11. The lower end of the pipe 25 is bent laterally and is disposed in communication with the inlet side 27 of a conventional air blower 26. The discharge 28 of this blower is connected by pipe 29 to a furnace 30 which may be heated by any suitable means. Disposed in communication with the top of the furnace 30 is an air pipe 31 which extends upwardly and is disposed in communication with the interior of the movable ironing head 14 as will be more fully explained hereinafter.

The movable or pressure head 14 comprises a longitudinal hollow casting 34 (Figures 5 and 6) which defines an air chamber 35. The bottom of this casting 34 is provided with a predetermined transverse curvature which is slightly greater than the curvature of the convex top 20 of the stationary buck. In other words, I provide the casting 34 of the ironing head 14 with a concave bottom 36 cooperable with the convex top 20 of the ironing head. This bottom 36 defines a concave ironing surface and is provided with perforations or openings 37. Also it is to be noted that this concave bottom has a layer of porous or filtering material 38 disposed thereover which is covered by a sheet of wire mesh 39. The layer 38 may be made of muslin or the like and serves to prevent dirt and soot from being forced into the article being ironed by the air under pressure in the head. The purpose of the mesh is to enhance the finish applied to the upper side of the article being ironed. This sheet of wire mesh may preferably be made of a highly polished sheet of No. 200 mesh (200 perforations to the inch) which has been heavily nickel plated.

I find that by nickel plating the mesh it results in the holes being reduced to almost pin holes which are sufficient to allow air to circulate therethrough without appreciably interfering with the polished ironing surface afforded by the mesh.

Also at this time attention is directed to the fact that the concave ironing surface of the pressing head 14 is provided with a curvature which is slightly greater than that of the convex top 12 of the buck 13. This means that as the head 14 is moved into cooperation with the article on the buck 13 it will cause the article to be thoroughly stretched thereon, thus eliminating wrinkles and other irregularities in the article being ironed.

Secured to the top of casting 34 are a pair of spaced arms 41 which are formed integral with a common pivotal member 42 journaled at its ends in the two arms 15 secured to the support 10. In Figure 6 it will be observed that the member 42 is provided with a hollow or air chamber 43 disposed in communication with the upper end of pipe 31. This upper end of the pipe 31 extends through one of the journaled ends of member 42 and is not secured to the member 42 so that relative movement can take place between member 42 and the pipe 31 as the ironing head 14 is moved into and out of cooperation with the stationary buck 13. Also threaded into the member 42 are three pipes, 44, 45, and 46 which extend through openings in the side of the casting 34 and into the air chamber 35. The pipe 45 is disposed in an intermediate position with respect to the pipes 44 and 46. The free ends of pipes 44 and 46 are bent laterally in opposite directions so as to be disposed in communication with the ends of the air chamber 35 as shown in Figure 6.

Also formed integral with the member 42 are a pair of spaced parallel arms 50 in which are journaled the ends of a pin or shaft 51. It will be noted that the intermediate portion of this shaft 51 is formed square. This shaft 51 has a central opening 52 through which extends the upper end of a rod 53. The extreme upper end of rod 53 is provided with a head 54 adapted to engage the top of shaft 51.

Surrounding the rod 53 below the shaft 51 is a spring 55, the lower end of which abuts a washer or shoulder 56 secured to an intermediate portion of rod 53. The extreme lower end of rod 53 is pivotally connected to the free end of a crank arm 57 which is secured to a shaft 58 rotatably carried by spaced brackets 59 and 60. Secured to this shaft between the brackets 59 and 60 (Figures 1 and 2) is a worm wheel 61 which meshes with a worm 62 secured to motor shaft 63 driven by an electric motor 64 of conventional construction. The worm 62 is connected to an intermediate portion of the shaft 63 which is journalled

in spaced brackets 65 and 66 between which the worm is disposed.

I desire it understood that although I have illustrated the air circulating means as being provided with a heater independent of the ironing machine for the purpose of simplifying the description of my ironing machine, the invention is not to be thus limited for obviously a heating unit such as that disclosed in my aforesaid co-pending application could be placed in either one of the ironing members of the present machine for heating the air being circulated.

The operation of my ironing machine is briefly as follows:

The normal or inoperative position of the ironing head 14 and the associated operating mechanism is shown in dotted lines in Figure 1.

Upon the operation of motor 64 through suitable switch mechanism (not shown), the crank 57 is moved to the uppermost position shown in full lines in Figure 1 and through the rod 53, and the associated mechanism causes the ironing head 14 to be moved down into cooperation with the stationary buck 13. Prior to the lowering of the head 14 an article is placed on the buck and is held in place on the convex surface by the suction in chamber 18. This article on buck 13 is thereafter engaged by the ironing head 14 and, due to the fact that the head 14 has a concave ironing surface of a slightly greater curvature than that of the convex top of stationary buck 13, the article is substantially stretched on the buck during the ironing operation.

The ironing of the article is effected by heated air forced by blower 26 from the furnace 30 into the chamber 35 of the head 14. This air applies heat to the highly polished sheet of mesh 39 which irons and finishes the article. Also through the means of the suction pipe 25 which is connected to the intake side of the blower 26, the heated air forced through the article is sucked away from the article and back into the furnace 30, thus augmenting and facilitating the cooling and drying of the article being ironed. By thus drying the bottom side of the article, the ironing surface of mesh 39 is enabled to cause both sides of the article to be given a soft finish. That is to say, the circulating air removes the moisture from the article and thus prevents the baking of water in the article whereby the article is not stiffened or given a hard finish.

Moreover, the suction of the convex surface of the buck serves to prevent irregularities from being formed in the article by the iron, and also enables a soft finish to be given the lower side of the article by removing moisture therefrom.

Now I desire it understood that although I have illustrated and described in detail the preferred form of my invention, the inven-

tion is not to be thus limited but only in so far as defined by the scope and spirit of the appended claims.

I claim as my invention:

5. 1. In combination, in an ironing machine, a pair of relatively movable and cooperable ironing members, means for enabling one of said members to be moved into and out of cooperation with the other of said members, 70
10 one of said members being provided with a convex ironing surface and the other of said members being provided with a concave ironing surface, said concave ironing surface having a curvature slightly greater than that of 75
15 the convex surface, whereby an article to be ironed, placed therebetween, will be stretched during the ironing operation.
2. In combination, in an ironing machine, a pair of relatively movable and cooperable 80
20 ironing members, means for circulating fluid through one of said members and through the article being ironed therebetween to iron and dry the article, and filter means in said member for filtering foreign matter such as 85
25 soot from said fluid being circulated prior to the fluid coming into contact with the article being ironed.
3. In combination, in an ironing machine, a pair of relatively movable and cooperable 90
30 ironing members, and means for circulating fluid through one of said members and through the article being ironed therebetween to iron and dry the article, one of said members having an ironing surface defined 95
35 by a polished sheet of perforated material adapted to be heated by the fluid forced therethrough for ironing and applying a high finish to the article being ironed.
4. In combination in an ironing machine, 100
40 a pair of cooperable and relatively movable ironing members for receiving between them and engaging an article to be ironed, and means for applying heated air to said members to provide heat for cooperating with 105
45 said ironing members to iron the article, said means comprising a blower connected to force the heated air into one of said members and to simultaneously suck the air out of the other member whereby the article is 110
50 dried during the ironing operation.
5. In combination with an ironing machine, a pair of cooperable ironing members for receiving between them and engaging an article to be ironed, means for forcing air 115
55 into and from one of said members to subject one side of the article being ironed to pressure, means for heating said air to provide heat for cooperating with the pressure to iron the article, and means for simultaneously 120
60 applying suction to the other ironing member to subject the other side of the article being ironed to remove substantially all moisture from said article whereby said article can be finished on both sides by the single ironing operation.
6. In combination in an ironing machine, a lower ironing member, an upper ironing member movable into pressure cooperation with said lower ironing member, and means for circulating heated air under pressure through said members including means for applying such air to the upper side of an article to be ironed and suction to the lower side of the article whereby to cause the article to adhere to the surface of said lower member in flat condition and to also remove substantially all moisture from the article simultaneously with the ironing operation. 125

7. The process of ironing an article which consists in applying pressure thereto and subjecting one side of the article to preheated air to supply heat for cooperating with the pressure to iron the article, and at the same time subjecting the article to suction for drawing the heated air therethrough to effect drying thereof while being ironed.
8. The process of ironing an article which consists in applying pressure thereto and stretching the article, and at the same time circulating heated gas through the article to supply heat for cooperating with the pressure to iron the article and to dry the article while being ironed.
9. The process of ironing an article which consists in applying pressure to the same, and while under such pressure subjecting one side only of the article to a source of heated gas under pressure to provide heat for cooperating with the pressure to iron the article, and at the same time subjecting the other side of the article to suction to augment the passage of heated gas through the article to dry the same while being ironed.
- In testimony whereof I have hereunto subscribed my name at Chicago, Cook County, Illinois.
- CHARLES O. REEPS.
